UNITED STATES PATENT OFFICE.

FRANK A. NIEBERDING, DECEASED, LATE OF EAST CLEVELAND, OHIO, BY MARGARET H. NIEBERDING, ADMINISTRATRIX, OF EAST CLEVELAND, OHIO.

BURNER.

Application filed November 5, 1925. Serial No. 66,988.

This invention relates to an improved burner for gas heaters, and the same is especially adapted, and is designed primarily, for use with so-called "radian" heaters in which foraminous commingling tubes of suitable refractory material, known as "radians", are supported above the burner openings and, when the heater is in operation, become more or less incandescent and give off a brilliant glow.

The burner is designed with a view of effecting and maintaining to the highest degree the relation of parts which is responsible for an equal distribution of the gas to all radians, and a proper control of primary and secondary air, to the end that the greatest economy and highest efficiency are obtained.

In addition to this, a fundamental object of the invention is to provide a burner of the aforesaid class in which the tubes that deliver gas to the individual radians are easily and quickly removable for cleaning purposes without disturbing any of the adjustments of the burner parts. The importance and desirability of this feature will be apparent to those acquainted with the fact that in the use of radiant gas heaters the burner openings have to be cleaned quite frequently if satisfactory results are to be obtained because the burner screens, wherewith the burner openings are equipped to prevent backfiring, soon become clogged with foreign matter, usually dust that is drawn in through the burner tube with the primary air.

In the accompanying drawings, wherein similar reference characters are used to designate corresponding parts throughout the several views, Fig. 1 is a front elevation and Fig. 2 a plan view of a burner constructed in accordance with the invention; Fig. 3 is a fragmentary sectional front elevation of the burner on a scale considerably enlarged over that of the preceding views; Fig. 4 is a fragmentary sectional plan, the plane of section being indicated by the line 4-4 of Fig. 3; Figs. 5 and 6 are sectional details on the lines 5-5 and 6-6, respectively, of Fig. 1, the same scale prevailing here as in Figs. 3 and 4; and Fig. 7 is a perspective view of one of the burner tubes.

The burner is made up of three major parts, to wit, a manifold, a radiant and burner

tube supporting frame, and burner tubes for the respective radians.

The manifold is designated 1, and it consists of a long hollow body that is shown as formed with equally spaced bosses 2 along its upper surface, and with an inlet extension 3 that, in the present instance, projects forwardly from the right hand end of the manifold, as the burner is viewed from the front.

A gas supply valve 5 is adapted to be connected, by a nipple 6, to the inlet extension 3. The burner is adapted to be supported from suitable parts of a heater structure through ears 7 that project forwardly and rearwardly from the opposite ends of the manifold and have perforations 8 for the accommodation of stove bolts or other securing means. The above mentioned bosses 2 are bored and tapped for the reception of nozzles 9. According to the present method of manufacture, the manifold 1 is cast, and core print openings in the end walls of the manifold are closed by plugs 10.

Extending upwardly from the manifold near each end is a riser 12 that is enlarged at its middle and bored and tapped for the reception of a screw 13 which serves to secure to the manifold the base 14 of the previously mentioned radiant and burner tube supporting frame. The base is positioned in a fore-and-aft direction with respect to the risers 12 by lugs 15 on the risers, whereby the connection between the base and manifold is thus rendered rigid and secure. Brackets 17 rise from the rear edges of the base 14, in

the zones of the risers 12, and resting upon these brackets are others designated 18 which depend from a head 20 that constitutes the other member of said radiant and burner tube supporting frame. The brackets 18 are formed with depending lugs 21 which are engaged over the front and rear corners of the brackets 17 for properly positioning the head 20 in a fore-and-aft direction with respect to the base 14, and the brackets 17 at the left hand end of the burner are equipped with lugs 22 which serve to relatively position the head and base in a longitudinal direction.

Securing means, such as stove bolts 23 to which nuts 24 are applied, are engaged through holes in the meeting ends of the brackets 17 and 18 and bind the head and base together. The head 20 is preferably

formed of an integral casting and comprises a bottom wall 25 and side walls 26, the latter being surrounded by radiant supporting and positioning lugs 27 on which radiants 28 are adapted to be supported. It will be noted that the upper ends of the lugs 27 are rabbeted to receive the radiants and support them at a given elevation.

The bottom wall 25 of the head 20 is provided with a series of apertures 30 which are in axial alignment with openings 31 in the base 14 and with the orifices of the nozzles 9. The openings 31 are surrounded by flanges 32 which have diametrically opposed notches 33. Downwardly tapering burner tubes 35 are adapted to be inserted, respectively, through the corresponding ones of the openings 30 and 31, and adjacent their lower ends said tubes have diametrically opposed projections 36 which are arranged to occupy the notches 33 of the flanges 32 and thus hold the tubes against angular movement and in proper position with respect to the nozzles 9. The tubes 35 are enlarged at their upper ends and terminate in rectangular frame-like portions 37 within which burner screens 38 are inserted, said screens serving to prevent backfiring of the gas into the tubes 35.

When the burner is in operation, the gas is projected by the nozzles 9 centrally within the tubes 35. The flow of gas induces an injection of air with the gas into the tubes where the air and gas are thoroughly mixed before they are emitted through the screen 38 immediately above which the mixture is adapted to burn. The spacing of the tubes from the nozzles 9 is in a given ratio to the area of the orifices of the nozzles so that a proper proportioning of the gas and air is assured. Secondary air is supplied to the flames above the burner tubes through the spaces between the lugs 27 and through openings 38 that are formed along the opposite sides of the head 20 at the angle between the bottom and side walls thereof. Additional secondary air enters through the openings in the radiants 28 to promote perfect combustion throughout the vertical extent of the radiants.

From the foregoing description it will be seen that the invention provides a very substantial and comparatively simple construction for gas burners wherein the parts are maintained in correct relative position to insure a proper supply of primary and secondary air; and by removing one or more of the radiants, any one or more of the tubes 35 may be lifted from the supporting frame and cleaned, should the screens 38 become clogged by dust or other foreign matter drawn in through the lower end of the tube by the suction created by the flow of the gas, or deposited upon the tops of the screens 38 from above. When the tube is dropped back through the openings 30 and 31 and the pro-

jections 36 are brought into register with the notches 33, a correct relation between the tube and nozzle 9 is assured, and the replacement of the radiant on the lugs 27 insures its proper location with respect to the upper end of the burner tube.

Having thus described the invention, what is claimed is:-

1. A gas burner comprising a radiant and burner tube supporting frame, a manifold situated below the frame and having gas emitting orifices, and burner tubes removably sustained by the frame free from the manifold so that the tubes may be readily lifted from the frame, the lower ends of the tubes being spaced above and disposed in operative relation to the gas emitting orifices, said tubes and said frame having coacting parts which position the tubes in operative relation to the gas emitting orifices. 85

2. A gas burner comprising a frame, a manifold situated below and secured to the frame, said manifold having a series of gas emitting orifices that are spaced apart along the upper side of the manifold, the frame having holes in axial alignment with said orifices, and burner tubes removably supported within said holes, the frame incorporating means for supporting radiants above and in operative relation to the upper ends of the burner tubes. 95

3. In a gas burner, the combination of a frame comprised of a head and a base connected together in vertically spaced relation, a manifold secured to and spaced below the base, said manifold having a series of longitudinally spaced apart gas emitting orifices, and the head and base having holes that are substantially in axial alignment with said gas emitting orifices, burner tubes removably supported within said holes in operative relation to the gas emitting orifices, the frame incorporating parts for supporting and positioning radiants in operative relation to the upper ends of the tubes. 100

4. In a gas burner, the combination of a frame comprised of a head and a base connected together in vertically spaced relation, a manifold secured to and spaced below the base, said manifold having a series of longitudinally spaced apart gas emitting orifices, and the head and base having holes that are substantially in axial alignment with said gas emitting orifices, burner tubes removably supported within said holes in operative relation to the gas emitting orifices, the tubes and frame having parts which coact to maintain the tubes in a given angular relation to the frame, the frame incorporating parts for supporting and positioning radiants in operative relation to the upper ends of the tubes. 115

5. In a gas burner, the combination of a frame comprised of a head and base that are connected together in vertically spaced relation, a manifold spaced below and connected 120

- to the frame and having a series of longitudinally spaced apart gas emitting orifices, the head and base of said frame having axially aligned openings that are substantially 5 in axial alignment with the orifices, burner tubes having their upper ends equipped with screens, said tubes being removably supported within the holes of the head and base, said tubes and the frame having cooperating 10 positioning parts whereby the tubes are held against turning with respect to the frame, the head incorporating means for supporting and positioning radiants in operative relation to the upper ends of the tubes.
- 15 6. In a gas burner, the combination of a frame comprised of a head and base that are connected together in vertically spaced relation, a manifold spaced below and connected to the frame and having a series of longitudinally spaced apart gas emitting orifices, the head and base of said frame having axially aligned openings that are substantially 20 in axial alignment with the orifices, burner tubes having rectangular upper ends equipped with screens, said tubes being removably supported within the holes of the head and base, said tubes having projections and the base having notches for the reception of said projections whereby the tubes are 25 held against turning with respect to the frame, the head incorporating means for supporting and positioning radiants in operative relation to the upper ends of the tubes.
- 30 7. In a gas burner, the combination of a frame comprised of a head and a base connected together in vertically spaced relation, a manifold secured to and spaced below the base and having a series of gas emitting orifices that are spaced apart longitudinally of 35 the manifold, the head and base having axially aligned openings that are substantially in axial alignment with said orifices, burner tubes removably supported within the openings of the head and base, the head having side walls and radiant supporting and positioning parts rising from said walls.
- 40 8. In a gas burner, the combination of a frame comprised of a head and a base connected together in vertically spaced relation, a manifold secured to and spaced below the base and having a series of gas emitting orifices that are spaced apart longitudinally of 45 the manifold, the head and base having axially aligned openings that are substantially in axial alignment with said orifices, burner tubes removably supported within the openings of the head and base, the head having side walls and radiant supporting and positioning parts rising from said walls, the head 50 being provided with secondary air openings.
- 55 9. In a gas burner, the combination of a frame comprised of a head and a base, the head consisting of a bottom wall and side walls and having adjacent its ends depending brackets, brackets rising from the base and 60 mating with those of the head, means securing the head and base together, the head and base having axially aligned openings, burner tubes removably supported individually within the corresponding holes of the head and base, the head incorporating lugs which rise from the side walls and are arranged to support radiants in operative relation to the upper ends of the burner tubes, and a manifold supported below the base and having gas emitting apertures in operative relation to the burner tubes.
- 65 10. In a gas burner, the combination of a frame comprised of a head and a base, the head consisting of a bottom wall and side walls and having adjacent its ends depending brackets, brackets rising from the base and 70 mating with those of the head, means securing the brackets of the head and base together, the head and base having axially aligned openings, burner tubes removably supported individually within the corresponding holes of the head and base, the head having a series of secondary air openings and incorporating lugs which rise from the side walls and are 75 arranged to support radiants in operative relation to the upper ends of the burner tubes, and a manifold supported below the base and having gas emitting apertures in operative relation to the burner tubes.
- 80 11. In a gas burner, the combination of a frame comprised of a head and a base that are connected together in vertically spaced relation, the head and base having axially aligned openings, burner tubes removably and individually supported in the corresponding openings of the head and base, the openings of the base being surrounded by flanges, the burner tubes having projections and said flanges having notches for the reception of said projections, and a manifold supported below the base and having gas emitting orifices in operative 85 relation to the burner tubes.
- 90 12. In a gas burner, the combination of a manifold having a series of gas emitting openings along its upper side that are spaced apart longitudinally of the manifold, the manifold being formed with risers adjacent its ends, a frame comprised of a head and a base that are connected together in vertically spaced relation, the base resting upon the risers of the manifold, means connecting the base to said risers, the head and base having vertically aligned openings that are substantially in axial alignment with the gas emitting orifices 95 of the manifold, and burner tubes removably and individually supported within the corresponding openings of the head and base.
- 100 13. In a gas burner, the combination of a manifold having a series of gas emitting openings along its upper side that are spaced apart longitudinally of the manifold, the manifold being formed with risers adjacent its ends, a frame comprised of a head and a base that are connected together in vertically spaced relation, 105 the base resting upon the risers of the manifold, means connecting the base to said risers, the head and base having vertically aligned openings that are substantially in axial alignment with the gas emitting orifices 110 of the manifold, and burner tubes removably and individually supported within the corresponding openings of the head and base.
- 110 14. In a gas burner, the combination of a manifold having a series of gas emitting openings along its upper side that are spaced apart longitudinally of the manifold, the manifold being formed with risers adjacent its ends, a frame comprised of a head and a base that are connected together in vertically spaced relation, 115 the base resting upon the risers of the manifold, means connecting the base to said risers, the head and base having vertically aligned openings that are substantially in axial alignment with the gas emitting orifices 120 of the manifold, and burner tubes removably and individually supported within the corresponding openings of the head and base.
- 120 15. In a gas burner, the combination of a manifold having a series of gas emitting openings along its upper side that are spaced apart longitudinally of the manifold, the manifold being formed with risers adjacent its ends, a frame comprised of a head and a base that are connected together in vertically spaced relation, 125 the base resting upon the risers of the manifold, means connecting the base to said risers, the head and base having vertically aligned openings that are substantially in axial alignment with the gas emitting orifices 130 of the manifold, and burner tubes removably and individually supported within the corresponding openings of the head and base.

tion, the base resting upon the risers of the manifold, the base and risers interengaging to position the frame in a given relation to the manifold, means connecting the base to said 5 risers, the head and base having vertically aligned openings that are substantially in axial alignment with the gas emitting orifices of the manifold, and burner tubes removably

and individually supported within the corresponding openings of the head and base.

In testimony whereof, I hereunto affix my signature.

MARGARET H. NIEBERDING,
Administratrix of the Estate of Frank A.
Nieberding.
